UNITED STATES PATENT OFFICE

MAX GREENAN, OF STATEN ISLAND, NEW YORK

DESIGN FOR AN ORNAMENTAL BIRD

Application filed June 18, 1930. Serial No. 36,085. Term of patent 7 years.

To all whom it may concern:

Be it known that I, MAX GREENAN, a citizen of the United States of America, and resident of Staten Island, in the county of Richmond and State of New York, have invented a certain new, original, and ornamental Design for Ornamental Bird, of which the following is a specification, reference being had to the accompanying drawing, forming part thereof.

The figure of the drawing is a perspective view of an ornamental bird showing my new design.

I claim:

The ornamental design for an ornamental bird, as shown.

MAX GREENAN.
